CLAIM

The ornamental design for character figure, as shown and described.

DESCRIPTION

FIG. 1 is a perspective view of a character figure incorporating the design of my invention;
FIG. 2 is a front view thereof;
FIG. 3 is a left side view thereof;
FIG. 4 is a right side view thereof;
FIG. 5 is a rear view thereof;
FIG. 6 is a top view thereof; and,
FIG. 7 is a bottom view thereof.

The broken lines shown in FIGS. 1 & 2 of the drawing are for illustrative purposes only and form no part of the claimed design.
